UNITED STATES PATENT OFFICE.

THOMAS M. CHANCE, OF WILKES-BARRE, AND EDWIN M. CHANCE, OF PHILADELPHIA, PENNSYLVANIA.

METHOD AND APPARATUS FOR THE DIFFERENTIAL DETECTION OF COMBUSTIBLE ATMOSPHERES.

1,298,890.

Specification of Letters Patent.

Patented Apr. 1, 1919.

Application filed May 1, 1917. Serial No. 165,722.

To all whom it may concern:

Be it known that we, THOMAS M. CHANCE and EDWIN M. CHANCE, citizens of the United States, and residing, respectively, at 5 Wilkes-Barre and Philadelphia, in the State of Pennsylvania, have invented a certain new and Improved Method and Apparatus for the Differential Detection of Combustible Atmospheres, of which the following 10 is a specification.

The object of our invention is to provide means whereby the presence of combustible gases in the atmosphere may be made known to the workmen, or others, where such conditions of the atmosphere may obtain. In an application for patent for improvement in method and apparatus for the detection of combustible and vitiated atmospheres, filed by us and dated April 14, 1917, we have disclosed 15 generic method and apparatus utilizing and comprising temperature responsive elements operatively connected to oral or visual signal devices, said elements being in operative relation to a source of heat. The 20 object of our present invention is the improvement in method and apparatus disclosed in said application, in which one combustible gas may be differentially detected 25 with reference to another.

To attain this end we provide a source of heat and an oxidizing material, both of said elements being in operative relation to temperature responsive elements operatively connected to aural or visual signal devices.

The drawing represents a vertical cross-section illustrating diagrammatically the general association of elements necessary to the operation of our invention.

In the drawing 1 indicates a tubular container filled with copper oxid 2, said copper oxid being so arranged in said tube and of such physical character as to be readily permeated by the atmosphere to be tested. A thermostatic device, in this case a tube 3 provided with an expansion chamber 4 and electrical contacts 5 and 6 (said tube and expansion chamber containing mercury 7) is arranged in operative relation to said con-

tainer 1 and said copper oxid filling 2. A source of heat 8 is provided in operative relation to said container 1 and copper oxid filling 2, this source of heat in this case consisting of a receptacle 9 filled with a liquid bath 10, an inlet 11 for the renewal of said bath and a heating coil 12 for maintaining 50 said bath at its boiling point. If desired a discharge 13 may be connected to said container 10, said discharge 13 conducting the vapor evaporated from said bath to a suitable condenser, from whence it may be returned to inlet 11. A casing 14 is adapted to inclose the apparatus, said casing being fitted with an inlet 15 and a discharge 16; the function of said casing being to provide 55 means whereby the atmosphere to be tested may be forced through the apparatus, drawn through by means of an exhauster, or in some cases automatically caused to flow through said apparatus by the chimney effect produced by source of heat 8; and 60 also to assist in isolating said apparatus from the exterior.

Electrical contact 5 is connected by means of circuit 17, source of electrical energy 18, electrically operated alarm 19 and circuit 20 to electrical contact 6, said contact 5 and 6 being adapted to be placed in circuit by the rising of mercury in tube 3. Foraminous means, in this case gauzes 21 and 22, may if necessary be provided for preventing propagation of flame to the exterior atmosphere, and, together with casing 14, completely isolating the apparatus from the exterior.

The operation of the apparatus illustrated is as follows: Assuming the apparatus to be 85 operating in normal atmosphere, the copper oxid filling 2 will reach its normal temperature and the mercury 7 will become heated thereby and rise to the level of normal operation indicated diagrammatically by the 90 line A—A. Circuits 17 and 20 will not be energized as, although contact 5 is covered by the mercury in the lower portion of tube 3 and expansion chamber 4, said mercury will not rise to the level of contact 6 under 95 conditions of normal operation.

If now an atmosphere containing a combustible gas, such as carbon monoxid, flow through the apparatus, heat will be generated by the oxidation thereof caused by 5 contact with copper oxid 2, the said copper oxid being maintained at a temperature which will cause the reduction of said oxid by carbon monoxid, but not at a high enough temperature to cause the combustion of the 10 carbon monoxid and the oxygen contained in the atmosphere. In other words, the copper oxid acts as a selective oxidizing agent for the oxidation of the carbon monoxid.

15 The mercury 7 is now further heated by the heat liberated during this reaction and expands, rising in tube 3 until, if the percentage of carbon monoxid be high enough to cause the required elevation in temperature, it makes contact with electric contact 20 6, closing circuits 17 and 20 and operating alarm 19, thus providing a warning of the presence of a certain percentage of carbon monoxid.

25 If hydrogen be passed through the apparatus it will operate the device in approximately the same manner as though carbon monoxid were present, but as these two gases are almost invariably associated in many locations where it is desirable to detect carbon monoxid, such as in coal mines, the fact that the hydrogen will also operate the apparatus merely serves to reinforce the carbon monoxid warning, and as the two gases if 30 simultaneously present will both assist in the operation of the apparatus, the combustion of the hydrogen will permit the detection of smaller quantities of the carbon monoxid than might otherwise be the case.

40 It will of course be understood that gases such as methane may be detected by the use of this apparatus provided that the oxidizing agent be maintained at a sufficiently high temperature to cause the oxidation of the 45 methane. This differential or selective action of the method is one of the principal objects of our invention, as it will enable the simultaneous and differential detection of different gases, such for example, as carbon 50 monoxid and hydrogen on the one hand and methane on the other hand.

To accomplish this end it is simply necessary to pass the suspected air through a plurality of apparatus of the type shown in 55 the figure, the first oxidizing chamber being maintained at a temperature that will oxidize the carbon monoxid and hydrogen but that will not affect the methane, and the second oxidizing chamber being maintained at a 60 temperature that will oxidize the methane. If it be desired to make a further differentiation, it will be possible to remove the carbon monoxid or hydrogen by passing it through

an oxidizing chamber maintained at a temperature that will oxidize the one but that is 65 too low to oxidize the other. It will of course be understood that when a plurality of combustion chambers are used for selectively detecting combustible gases of different composition, the signaling devices connected to the various combustion chambers 70 may be separate so that a separate signal will be given for each gas that it is desired to detect.

It should be noted that as atmospheric 75 oxygen is not used in the oxidation of the combustible gases to be detected, the method and apparatus will function in vitiated atmospheres that would not support the combustion of these combustible gases, due to 80 the low oxygen percentage, or even to the absence of oxygen.

As the maximum temperature that will be reached by any definite percentage of the combustible gas is fixed by, 1, the heat of 85 combustion of the gas, 2, the rate of flow of the gas, or gas and air, through the apparatus and 3, the rate of heat loss of the apparatus as a whole, it will be clear that the two latter quantities are possible of control and 90 that all three may be considered as constant for any given apparatus. Hence it is readily possible to so fix their relation that a definite predetermined percentage of the gas to be detected will be required to cause the 95 operation of the thermostatic device and warning signal. Physical properties of the gas, such as specific heat, etc., may be considered to be approximately constant for the 100 purpose of the operation of the apparatus.

It will be desirable to restrict the flow of the air, or gas and air, to be tested through the apparatus in order to keep the conditions constant, as outlined in the preceding paragraph. It is also necessary to maintain the oxidizing material at an approximately uniform temperature, and in certain cases this may be readily attained by preheating the air, or gas and air, to the desired temperature prior to passing it over the oxidizing material. In such cases it will not always be necessary to heat extraneously the oxidizing material, as the air to be tested may perform this function.

In certain cases a catalytic oxidizing material may be used, as for example, when hydrogen is to be detected, and under these conditions the initial rise in temperature of the oxidizing element may be caused, or assisted, by catalytic action.

It will be understood that a great variety of devices may be used in the operation of our method and in the construction of apparatus therefor, and it has not been deemed necessary to illustrate and describe at length 125 a great number of different types and modi-

ifications of such apparatus. For example, the thermostatic element may be widely varied, as any type of thermostatic device in common use may be employed provided it possesses the necessary operating characteristics. While the drawing shows an electrical connection between the signaling means and the thermostatic element, it will of course be understood that other devices 10 may be used therefor.

It will be understood that the invention may be employed in either a stationary or portable form, and that one or more detectors may operate by remote control a single signal or that a plurality of signaling devices may be operated by one or more detectors.

In the application for patent dated April 14, above referred to, a number of modifications of apparatus are shown for carrying out the generic method of gas detection therein described and claimed, and it will be understood that many of these modifications may be employed with the present invention and also that the subject matter described and claimed herein is subject to the dominating features of the disclosures in said application for patent.

The operation of our invention is not limited to the use of copper oxid but depends upon the use of any metal, or metalloid, compound, containing oxygen, which when maintained at suitable temperature will cause the desired oxidation of the combustible gas which is to be detected, and the term "oxidizing agent" in the claims hereof, is used to designate such compound.

In the operation of our invention it will of course be understood that the oxidizing agent, such as copper oxid, will become reduced by the passage of the combustible gas through it and that this oxidizing agent may either be renewed from time to time or may be re-oxidized by the action of a 45 strongly oxidizing atmosphere.

Having described our invention we claim:

1. The method of detecting changes in the constituent gases of the atmosphere which consists in maintaining a temperature responsive element in operative relation to an oxidizing agent and to a source of heat, said element being operatively connected to signaling means; in causing said element to operate said signaling means when the temperature of said element reaches a predetermined limit; and in permitting variations in the heat received from said source of heat, due to the chemical reduction of said oxidizing agent caused by changes in said constituent gases, to cause the temperature of said element to reach said limit; whereby said signaling means are operated and a warning of said changes given.

2. The method of detecting changes in the constituent gases of the atmosphere which consists in maintaining a temperature responsive element in operative relation to an oxidizing agent and to a source of heat, said element being electrically connected to signaling means; in causing said element to operate said signaling means when the temperature of said element reaches a predetermined limit; and in permitting variations in the heat received from said source of heat due to the chemical reduction of said oxidizing agent caused by changes in said constituent gases, to cause the temperature of said element to reach said limit; whereby said signaling means are operated and a warning of said changes given.

3. The method of detecting changes in the constituent gases of the atmosphere which consists in maintaining a temperature responsive element in operative relation to an oxidizing agent and to a source of heat, said element being operatively connected to signaling means; in causing said element to operate said signaling means when the temperature of said element reaches a predetermined limit; and in permitting variations in the heat received from said source of heat, due to the chemical reduction of said oxidizing agent caused by changes in said constituent gases, to cause the temperature of said element to reach said limit; whereby said signaling means are operated and a warning of said changes given, means being provided for preventing propagation of flame to the exterior.

4. The method of detecting changes in the constituent gases of the atmosphere which consists in maintaining a temperature responsive element in operative relation to an oxidizing agent and to a source of heat, said element being electrically connected to signaling means; in causing said element to operate said signaling means when the temperature of said element reaches a predetermined limit; and in permitting variations in the heat received from said source of heat, due to the chemical reduction of said oxidizing agent caused by changes in said constituent gases, to cause the temperature of said element to reach said limit; whereby said signaling means are operated and a warning of said changes given, means being provided for preventing propagation of flame to the exterior.

5. Apparatus for the detection of changes in the constituent gases of the atmosphere, comprising in combination an oxidizing agent, a source of heat in operative relation thereto, a temperature responsive element in operative relation to said agent, and signaling means operatively connected to said temperature responsive element.

6. Apparatus for the detection of changes
in the constituent gases of the atmosphere,
comprising in combination an oxidizing
agent, a source of heat in operative relation
5 thereto, a temperature responsive element in
operative relation to said agent, and elec-
trical signaling means operatively connected
to said temperature responsive element.

In testimony whereof THOMAS M. CHANCE
10 has signed his name at Philadelphia, Penn-
sylvania, the 28th day of April, 1917, and

EDWIN M. CHANCE has signed his name at
Wilkes-Barre, Pennsylvania, the 30th day
of April, 1917.
